JULIAN L. PERKINS, OF WEST SPRINGFIELD, AND HIRAM D. CROFT, OF SPRINGFIELD, MASSACHUSETTS, ASSIGNORS TO PERKINS MACHINE AND GEAR COMPANY, OF WEST SPRINGFIELD, MASSACHUSETTS, A CORPORATION OF MASSACHUSETTS

STARTING AND STOPPING MECHANISM

Application filed September 20, 1928. Serial No. 307,260.

Our invention relates to improvements in mechanisms for engaging and disengaging driving elements or parts with and from driven elements or parts which constantly 5 rotate; and the primary object of our invention is to produce convenient, positive, and highly efficient, yet comparatively simple, mechanism for starting, maintaining in action, and stopping oscillatory members driven 10 from constantly rotating members, which mechanism is especially well adapted for a washing machine wherein there is driving mechanism, usually receiving power from an electric motor, an oscillatory tub, and a 15 wringer, and it is desired that the tub remain stationary while the wringer is in operation. This starting and stopping mechanism affords means for setting in motion the tub of a washing machine, and causing the same to stop 20 moving, at will, without disturbing the mechanism which drives both said tub and the associated wringer.

Although our starting and stopping mechanism is designed more particularly for washing machines, the same is applicable to other machines wherein there are parts requiring independent motive control.

Other objects and advantages will appear in the course of the following description.

We attain the objects and secure the advantages of our invention by the mechanism illustrated in the accompanying drawings, in which—

Figure 1 is a top plan, with parts broken away and in section, of a washing machine equipped with starting and stopping mechanism which embodies a practical form of our invention, and, Fig. 2, a side elevation in partial section of said machine and mechanism.

Similar reference characters designate similar parts throughout the several views.

The parts of the washing machine illustrated in the drawings are briefly described as follows:

A transmission case is represented at 1. This case has at one end two oblique arms 2 which support said case at that end on two wheels 3, and the opposite end of the case is 50 supported by a foot 4. Secured to the end of

the case 1 where the arms 2 are located, which is the rear end of said case and of the machine, is an electric motor 5, said motor being between said arms and the wheels 3. The case 1 has a cover 6. Journaled in a bearing 7 in 55 the front side of and in a bearing 8 within the case 1 is a horizontal shaft 9 on which is mounted and secured a worm 10. The shaft 9 extends beyond the outer end of the bearing 7, and has mounted on and secured to the protruding terminal a pulley 11. The motor 5 has a shaft 12 projecting behind the outer terminal of the shaft 9, and on which is mounted and secured a pulley 13. A belt 14 connects the pulleys 11 and 13, and the worm 10 is driven from the motor 5 through the medium of the shaft 12, said pulleys and said belt, and the shaft 9.

Adjacent to the front end of the case 1 is a vertical socket 15 for the foot 4, and to provide a bearing for a worm-wheel 16. The worm-wheel 16 intermeshes with the worm 10. Rising from the cover 6 above the socket 15 is a wringer column 17. A vertical shaft 18 has its lower terminal secured to the worm-wheel 16 by which said shaft is driven. The shaft 18 extends upwardly through the column 17, and is the driving shaft for the wringer (not shown). The lower terminal of the column 17 is received in and supported 70 by a flange 19 mounted on and rigidly connected with the cover 6. A horizontal pin 20 extends from the interior of the column 17 through said column and the flange 19 and projects outside of said flange, said pin being at right-angles to the vertical plane in which are located the axes of the shaft 18 and a shaft 23. The projecting part of the pin 20 is on the same side of the machine as are the projecting parts of the motor and worm 75 shafts, and is a part of the stopping and starting mechanism.

The case 1 and the cover 6 adjacent to their rear ends are respectively provided with under and upper bearings 21 and 22 for the shaft 23, and mounted on and secured to said shaft between said bearings is a pinion 24. Mounted on and secured to the shaft 23 at the upper terminal is a hub 25 of a holder 26 for a tub (not shown).

The worm-wheel 16 is provided on top with an eccentric 27, encircling which is a ring 28. The ring 28 is an integral part of a rack 29 which extends rearwardly from said ring into position to engage the pinion 24, the teeth of said rack being on the front or forward edge thereof.

It will now be seen that, when the motor 5 is in operation, the shafts 9 and 18 are constantly rotated, and the rack 29 is constantly reciprocated, the reciprocating motion being imparted to said rack by the eccentric 27.

Loosely mounted on the flange 19, and supported by the cover 6, is a hub 30, from which extend radially a handle 31 and an arm 32, said handle and arm being somewhat less than ninety degrees apart, and the former extending over the front end and the latter toward the back side of the cover 6. The top of the hub 30 is cut away to form a recess 33 into which the pin 20 projects. Thus the pin 20 holds the hub 30 down on the cover 6, and limits the amount of rotation permitted said hub on the flange 19, by being in the paths of the ends of the recess 33. The free end of the arm 32 is thickened and rounded substantially as shown at 34.

Journaled in a bearing 35 in the bottom of the case 1, and in a bearing 36 in the top of the cover 6, is a vertical rock shaft 37. The shaft 37 is behind the aforesaid vertical plane in which the axes of the shafts 18 and 23 are located, but nearer to said second-named than to said first-named shaft. A rod 38 has its rear end rigidly connected with the upper terminal of the shaft 37, which terminal is above the cover 6, and said rod extends toward the front end of the machine into the path of the arm 32. Rigidly attached to the shaft 37, within the case 1, is a rocker arm 39 which extends toward the rear end of the machine, and is provided with a roll 40, said roll having a shaft 41 journaled in said arm at the back end thereof. The rear terminal of the arm 39 is bifurcated to receive the roll 40.

The hub 30 with its handle 31 and arm 32, and the rock shaft 37 with its rod 38 and arm 39, together with the oscillatory rack 29, comprise stopping and starting mechanism for the shaft 23 which oscillates the tub holder 26, and the parts and members of said mechanism are constructed, proportioned, and arranged to function and bring about the results described below.

When the hub 30 is positioned with the left-hand end of the recess 33 in engagement with the pin 20, the outer end of the arm 32 is in contact with the free terminal of the rod 38, and the roll 40 is caused to bear hard on the back edge of the rack 29, and retain said rack in full engagement with the pinion 24, as illustrated in full lines in the first view. The oscillatory movement of the rack 29 is now imparted to the pinion 24, and b.

70 latter to the shaft 23 and the tub holder 26, assuming, of course, that the motor is in operation. At this time the handle 31 is in the aforesaid vertical plane. Upon grasping the handle 31 and swinging it rearwardly or toward the back side of the machine, until the right-hand end of the recess 33 encounters the pin 20, the arm 32 is moved into a position to release the rod 38, when the action of the eccentric 27 on the ring 28 partially rotates said ring in the direction to swing the rack 29 out of engagement with the pinion 24, the arm 39 and said rod rocking on and with the shaft 37 as said rack moves the roll 40 and the rear end of said arm outwardly and said rod, through the medium of said shaft, inwardly at the free terminal. An outward swing is imparted to the rack 29 because the eccentric 27 is rotated to the left.

75 80 85 When the rod 38 is swung inwardly, the free terminal portion thereof is received against a flattened part of the hub 30, which flattened part forms a rest or stop which appears at 42. This stop limits the outward movements of the rocker arm 39 and the rack 29.

90 95 The rack 29 is now entirely clear of the pinion 24, and retained in contact with the roll 40 by the action of the revolving eccentric 27.

The instant disposition of the parts and members of the starting and stopping mechanism is indicated by the broken or dotted lines in the first view.

100 105 110 When the handle 31 is returned to its former position, the hub 30 is rotated or partially rotated, in the opposite or reverse direction, until the left-hand end of the recess 33 encounters the pin 20, and said hub carries with it the arm 32 which engages the rod 38 and swings said rod outwardly, with the result that the arm 39 is swung inwardly, and, through the medium of the roll 40, moves the rack 29 into engagement again with the pinion 24, thus once more setting in motion the tub holder 26, provided the driving mechanism be in action.

115 The rack 29, in swinging into and out of engagement with the pinion 24, rocks on and with its ring 28 as the latter is then partially rotated on the eccentric 27. This is true whether or not the eccentric be in motion.

120 125 The arm 32 must be of sufficient length to cause the rack 29 to be moved into full engagement with the pinion 24, and, preferably, the rod 38 is somewhat resilient so that the same, when moved outwardly at its free terminal by the arm 32 to the full extent, causes the roll 40 to be held against the rack 29 with some little force. While the rod 38 is held outwardly to the full extent by the arm 32, the pinion 24 must be oscillated by the rack 29 if in motion.

130 When the left-hand end of the recess 33 is in engagement with the stop pin 20, whereby

further rotation to the left of the hub 30 is prevented, the arm 32 and that part of the rod 38 that is between said arm and the shaft 29 form an acute-angle with each other, consequently said arm and said rod can not become accidentally disengaged, as might be the case if they formed a right-angle with each other. In other words, the arm 32 is moved past the center and into locking position relative to the rod 38, when the hub 30 is rotated or partially rotated to the left as far as the pin 20 permits.

More or less change in the shape, size, construction, and arrangement of some or all 15 of the parts of this mechanism may be made, without departing from the spirit of our invention, or exceeding the scope of what is claimed.

We claim:

1. In mechanism of the class described, a 20 rotatable member, an eccentric, an oscillatory member driven by said eccentric, and adapted to be swung thereon into and out of engagement with said rotatable member, and means to actuate said oscillatory member into such engagement, and permit it to become disengaged, said eccentric rotating in a 25 direction tending to actuate said oscillatory member out of engagement with said rotatable member.

2. The combination, in mechanism of the 30 class described, with a pinion, and an eccentric driven rack adapted to be swung on the eccentric into and out of engagement with 35 said pinion, of a rocker arm in operative position relative to said rack, and adapted to actuate said rack into engagement with said pinion, and to release it from such engagement, and yielding means to actuate said 40 rocker arm in the direction to force said rack into engagement with said pinion.

3. The combination, in mechanism of the 45 class described, with a pinion, and an eccentric driven rack adapted to be swung on the eccentric into and out of engagement with 50 said pinion, of an oscillatory arm, a rock shaft, a rocker arm carried by said shaft in operative position relative to said rack, and a rod carried by said shaft in operative position relative to said oscillatory arm, whereby 55 the latter when moved in one direction causes said rod and said rocker arm to move said rack into engagement with said pinion, and when moved in the other direction permits said rack to be disengaged from said pinion.

4. The combination, in mechanism of the 60 class described, with a pinion, and an eccentric driven rack adapted to be swung on the eccentric into and out of engagement with 65 said pinion, of a rotatable hub provided with a handle and an arm, a rock shaft, a rocker arm carried by said shaft in operative position relative to said rack, and a rod carried by said shaft in the path of said first-named arm, whereby the movement of said handle

in one direction causes said rack to engage said pinion, and movement of said handle in the other direction permits said rack to become disengaged from said pinion.

5. The combination, in mechanism of the 70 class described, with a pinion, an eccentric driven rack adapted to be swung on the eccentric into and out of engagement with said pinion, and a supporting member provided with a projection, of a hub, provided with a handle and an arm, mounted on said member, and cut away to receive said projection, whereby the rotary movement of said hub on said member is limited, a rock shaft, a rocker arm carried by said shaft in operative position 75 relative to said rack, and a rod carried by said shaft in the path of said first-named arm, whereby the movement of said handle in one direction causes said rack to engage said pinion, and movement of said handle in the other direction permits said rack to become 80 disengaged from said pinion.

6. The combination, in mechanism of the 85 class described, with a rotary member provided with an eccentric, a rack having a ring 90 encircling said eccentric, a pinion with and from which said rack is adapted to be engaged, and a supporting member, of a hub provided with a handle and an arm mounted for rotation on said supporting member, a 95 rock shaft, a rocker arm carried by said shaft in operative position relative to said rack, and a rod carried by said shaft in the path of said first-named arm, whereby the movement of said handle in one direction causes said rack to engage said pinion, and movement of said handle in the other direction permits said rack to become 100 disengaged from said pinion.

7. The combination, in mechanism of the 105 class described, with a pinion, and an eccentric driven rack adapted to be swung on the eccentric into and out of engagement with said pinion, of an oscillatory arm, a rock 110 shaft, a rocker arm carried by said shaft in operative position relative to said rack, and a resilient rod carried by said shaft in operative position relative to said oscillatory arm, whereby the latter when moved in one direction causes said rod and said rocker arm to move said rack into and yieldingly hold it in engagement with said pinion, and when moved in the other direction permits said rack to be disengaged from said pinion.

8. The combination in mechanism of the 120 class described, of a rotatable shaft and an oscillatable shaft, an eccentric on said rotatable shaft and a pinion on said oscillatable shaft, a member on said eccentric adapted to be reciprocated thereby and having teeth for engaging said pinion, an oscillatable lever for holding said rack in engagement with said pinion, a rod extending from said lever towards said rotatable shaft and a second lever oscillatable axially of said rotatable 125 shaft.

shaft for engaging and swinging said rod whereby said first-named lever may be operated by the latter for engaging said rack with said pinion.

- 5 9. The combination in mechanism of the class described of, a rotatable shaft having an eccentric fixed thereon, an oscillatable shaft having a pinion fixed thereon, a member in rotatable engagement with said eccentric having a toothed end for engaging said pinion and adapted to swing towards and away from said pinion, a lever mounted for swinging movements for engaging the toothed end of said member and swinging the same into engagement with said pinion, a rod extending from said lever towards said rotatable shaft, a second lever arranged for swinging movements axially of said shaft for swinging said first-named rod and lever and 10 a stop associated with said second lever for engaging said rod to limit the relative movement thereof.
